Design No 439.

John Burgess Assignor to
Messrs. G. A. Chaffee & Richmond. Stove Design

Patented Jan'y 13. 1852.

John Burgeff a/s to Gen. Chaffee & Richards of Troy N.Y.
Letters Patent No 439 Dated Jan 10 1852

The schedule referred to in these Letters Patent and making part of the same

To all to whom these presents shall come.

I John Burgeff

Be it Known that

I John Burgeff of Troy in the County of Rensselaer and State of New York have invented or produced a new design of coal burner stove which I call the "pagoda" and I do hereby declare that the following is a full clear and exact description of the same, reference being had to the annexed drawing, making a part of this specification which is a side elevation of the stove, which is a copy of either of the four sides.

The design of my stove consists principally of Gothic architecture and arabesque figures. It is formed in three panel sections one above the other in a conical structure, the ornaments in the lower section is formed in a square panel, the figures consisting of arabesque and other ornaments, a, b, c, d & e. The second section consists of a Gothic door panel and ornaments ff and the third a window panel of the same order as the second and ornaments gg, and each section is surmounted with cornices h. i j ornaments with arabesques as represented.

Having thus described, and represented my new design what I claim is the design, and configuration of a cast stove substantially the same, as described, and represented in the annexed drawing

Witnessed
